UNITED STATES PATENT OFFICE.

WALTER J. MILLOWAY, OF LARNED, KANSAS.

GRAIN-DOOR.

1,051,965.

Specification of Letters Patent.

Patented Feb. 4, 1913.

Application filed May 8, 1912. Serial No. 695,938.

To all whom it may concern:

Be it known that I, WALTER J. MILLOWAY, a citizen of the United States, residing at Larned, in the county of Pawnee and State 5 of Kansas, have invented a new and useful Grain-Door, of which the following is a specification.

One object of the present invention is to provide a grain door for a car, which door 10 may readily be slid to one side, when not in use, a compartment being provided within the car, within which compartment the door is adapted to be received when not in use.

15 A further object of the invention is to provide means whereby access may be had to the compartment to afford a cleaning of the tracks, within the compartment, upon which tracks the door is adapted to slide.

20 A further object of the invention is to provide novel means for holding the door in housed position within the car and to provide means whereby the door may readily slide outwardly, to extend across the 25 doorway.

With the foregoing and other objects in view, which will appear as the description proceeds, the invention resides in the combination and arrangement of parts and in 30 the details of construction hereinafter described and claimed, it being understood that changes in the precise embodiment of invention herein disclosed can be made within the scope of what is claimed without departing from the spirit of the invention.

In the drawings,—Figure 1 shows in elevation, a portion of the inside of a car, equipped with the door constituting the subject-matter of the present invention; Fig. 40 2 is a section on the line 2—2 of Fig. 1; Fig. 3 is a section on the line 3—3 of Fig. 1; Fig. 4 is a fragmental detail in vertical section, showing the coöperation between certain of the door-securing elements; and Fig. 45 5 is a fragmental section of the door.

In the drawings, the numeral 1 indicates a portion of the side wall of a car, the numeral 2 indicating a portion of the flooring. One door post is indicated by the numeral 3 and the other door post is indicated by the numeral 4. The wainscoting of the car is denoted by the numeral 5, and the upper edge of the wainscoting 5 is connected with the side wall 1 of the car by means of a 55 top plate 6, the flooring 2, the wainscoting

5, the top plate 6 and the outer wall 1 of the car defining a compartment, denoted by the numeral 7, the door post 3 extending across one end of the compartment 7. A movable closure 8 is provided, giving access 60 to the compartment 7, the closure 8 being hinged to the lower end of the wainscoting 5, as denoted by the numeral 9. The door is denoted generally by the numeral 10 and may be fashioned in any desired manner, 65 it being preferable that the door 10 be an iron or metal structure. The door 10 is adapted to slide through the door post 3, the post being slotted to permit the passage of the door, and a groove 11 is provided upon the door post 4, in which groove the free end of the door 10 is received, to prevent the door from bulging outwardly under the weight of the grain within the car. Preferably the door 10 comprises a 70 plate 12, a top rail 14, a bottom rail 15, end bars 16, an intermediate bar 17 and cross braces 18. The door 10 is supported for sliding movement upon rollers 19 carried by shafts 20, the ends of the shafts 20 80 preferably being received within the bottom rails 15. The rollers 19 are adapted to move between the tracks 21 secured to the floor 2 within the compartment 7, the tracks 21 extending out of the compartment 85 and across the doorway to a point adjacent the door post 4.

A means is provided for holding the door housed within the compartment 7. This means preferably includes a pin 21' secured 90 to the door post 3 by means of a flexible element 23. The pin 21' is adapted to be inserted through an opening 24 in the top plate 6, the lower end of the pin 21' registering in an opening 25 which is fashioned 95 in the upper edge of the door 10. A portion of one of the end bars 16 is cut away to define a recess 16' in which is located a lever member 26 pivotally supported upon the door as indicated at 27, the inner end of 100 the lever 26 terminating in a cam 27, adapted to engage the pin 21'.

The operation of the device is as follows:—The free end of the lever 26 may be swung outwardly, when the door 10 is within the compartment 7, thereby affording a convenient handle whereby the door may be slid across the doorway, the door moving between the tracks 21 and registering ultimately in the groove 11 as will be under- 110

stood readily. When the occasion for the use of the door 10 has passed, the door may be slid rearwardly through the door post 3 into the compartment 7. When the door is thus housed within the compartment, the pin 21' may be inserted through the opening 24 in the top plate 6, and into the opening 25 in the door 10, the door 10 being thus held housed within the compartment 7.

10 When the lever 26 is swung into a depending position, the cam 28, will engage with the pin 21' thus holding the pin fixed against displacement. Moreover, when the lever 26 is thus engaged with the pin, the lever cannot swing and clatter about.

15 If desired, the door 10 may be equipped with an auxiliary door 50, which door 50 may be opened when the door 10 is closed, for the purpose of relieving the pressure of the grain against the door 10, so that the same may be moved to an open position.

Having thus described the invention, what is claimed is:—

In a device of the class described, a supporting structure provided with a compartment; a door mounted to slide into the compartment; a pin insertible into the compartment, there being an opening in the door, in which opening the pin is adapted to be received; and a lever pivoted to the door and adapted to protrude beyond the door to constitute a means for moving the door, the lever having a cam portion adapted to engage the pin, to maintain the pin engaged with the door.

In testimony that I claim the foregoing as my own, I have hereto affixed my signature in the presence of two witnesses.

WALTER J. MILLOWAY.
